DESIGN FOR A COMBINED ELECTRIC SWITCH PLATE ATTACHMENT AND CAL- ENDAR

Harry M. Kidd, El Paso, Tex.

Application October 29, 1938, Serial No. 80,765

Term of patent 3½ years

To all whom it may concern:

Be it known that I, Harry M. Kidd, a citizen of the United States and resident of El Paso, in the county of El Paso and State of Texas, have invented a new, original, and ornamental Design for Combined Electric Switch Plate Attachment and Calendar, of which the following is a specification, reference being had to the accompanying drawing, forming part thereof.

Fig. 1 is a view in front elevation of a combined electric switch plate attachment and calendar showing my new design;

Fig. 2 is a view in side elevation thereof.

I claim:

The ornamental design for a combined electric switch plate attachment and calendar, substantially as shown.

HARRY M. KIDD.
